HANS KREIDEL, OF WIESBADEN, GERMANY

GREASE GUN

Application filed April 11, 1928, Serial No. 269,223, and in Germany March 2, 1928.

The present invention relates to a lubricating gun having a suction and pressure piston adapted to be actuated by hand, the front portion of the gun being formed as a high pressure pump mechanism of which the spring actuated working and sliding cylinder guided in the bottom of the gun forms a common outflow passage for the lubricant and in which the high pressure pump mechanism automatically comes into operation as soon as a higher resistance is opposed to the outflow of the lubricant and the outflow nozzle must be pressed more strongly upon the point to be lubricated, the entire lubricating gun now sliding forwardly on the working and sliding cylinder and the ejection piston of the high pressure pump mechanism enters the cylinder. The lubricating gun may be used as an ordinary lubricating gun and as a high pressure lubricating gun. In the first method of operation the complete charge of lubricant can be ejected successively in small quantities or also at one operation by means of the suction and pressure piston. In the second method of operation, however, it is only possible to effect the ejection in separate quantities, under high pressure, which correspond to the amount by which the ejection piston of the high pressure pump mechanism penetrates into the working and sliding cylinder is preferably constructed without valves so that by means thereof, when withdrawing the suction and pressure piston provided in the gun cylinder, the lubricant is also drawn from a supply container, the lubricating gun being thus capable of being filled in a simple manner. The working and sliding cylinder and the ejection piston of the high pressure pump mechanism are under the action of a single spring which forces them axially apart, this spring holding both the cylinder head against the bottom of the gun, and also pressing the perforated supporting plate or the supporting bar of the ejection piston on a shoulder of the gun cylinder in a manner as to be detachable and removable. The packing of the working and sliding cylinder in the bottom of the gun is effected by means of a packing disc fitted over and bearing against the latter, which disc is alternately exposed to the action

of the spring of the high pressure pump mechanism and the pressure of the lubricant.

The accompanying drawings show an example of construction in accordance with the invention in longitudinal section, in four different positions.

Figure 1 shows the lubricating gun in the position of rest, completely empty and with a protecting cap screwed over the working and sliding cylinder and the nozzle.

Figure 2 shows the lubricating gun with the nozzle inserted in the supply of lubricant, whilst the gun suction and pressure piston is drawn back and consequently has effected the filling of the gun.

Figure 3 shows the lubricating gun when lubricating a ball bearing when no friction is opposed, and

Figure 4 shows the high pressure pump mechanism in operation for overcoming a resistance which is opposed to the outflow of the lubricant when lubricating a sliding bearing.

a indicates the gun cylinder for the reception of the lubricant and provided with a bottom *b* and a cover *c*. By means of a depression formed in the cylinder there is obtained an inwardly directed projection or shoulder *d*. Above this is located the suction and pressure piston *e* of the gun, of which the piston rod *f* is passed through the cover *c* and outside is provided with a suitable hand-piece *g*. This suction and pressure piston *e* consists of two leather cups having the bottoms thereof pressed against one another or together by means of a spring *e¹* bearing against a disc *f¹* secured to the end of the piston rod.

In the front portion of the gun cylinder *a* there is mounted the high pressure pump mechanism. This consists of the valveless working and sliding cylinder *h* and the ejection piston *i* between which is located the compressible spring *k* which moves them axially apart. The working and sliding cylinder *h* is guided in the strengthened portion of the gun bottom *b* and is provided with a separate nozzle *l* for application to the point to be lubricated. Instead of the nozzle shown any other suitable nozzle may be used. On the working and sliding cylinder *h* there is

fitted a packing disc *m* of leather or the like which tightly surrounds it and bears loosely against the gun bottom *b*. The strengthened head *h*¹ of the working and sliding cylinder also bears against the gun bottom or the packing disc *m* placed thereon and against the somewhat enlarged end thereof bears the compressible spreading spring *k*. In the head of the working and sliding cylinder *h* is secured a packing disc *n* of leather or the like which serves for packing the ejection piston *i* relatively to the internal space of the working and sliding cylinder. The ejection piston *i* is secured to an annular disc *o* provided with passages *o*¹, which disc *o* is constantly pressed against the inner rib or shoulder *d* of the gun cylinder *a*. The gun bottom *b* is provided with an outwardly extending screwed extension *b*¹ on which there may be screwed, when the lubricating gun is not in use, a cap *p* for protecting the projecting part of the working and sliding cylinder and the nozzle thereof. When the gun is to be used the cap is removed. When it is desired to fill the lubricating gun with lubricant the nozzle *l* is dipped into the supply of lubricant and the suction and pressure piston *e* is drawn back in the direction of the arrow. (Figure 2.) As this can only be moved as far as the rib or shoulder *d* air is contained in the front portion of the lubricating gun cylinder, containing the high pressure pump mechanism, before the lubricating gun is used for the first time, which air must be ejected by moving the suction and pressure piston to and fro a number of times.

When all the air has been removed then on pulling back the suction and pressure piston *e* lubricant is drawn in thus flowing through the nozzle *l* and the working and sliding cylinder *h* and past the ejection piston *i* and finally through the openings *o*¹ in the annular disc *o* to below the suction and pressure piston and filling the entire free space of the gun cylinder *a*. If it is now desired to operate upon a point to be lubricated with the lubricating gun which is now ready for use and which point does not oppose any resistance to the lubricant, as is for example the case when lubricating and filling ball bearings, (Figure 3) and annular bearings or when filling lubricant containers of different types, as also when simply ejecting the lubricating material, as is the case with the usual lubricating gun, slight pressure on the hand-piece *g* of the suction and pressure piston *e*, in the direction of the arrow (Figure 3), suffices to cause the lubricant to flow out and flow into the point to be lubricated or into the container in question.

As soon as any considerable resistance is opposed to the lubricant at the point of leaving the nozzle, as is for example the case when lubricating sliding bearings (Figure 4)

a higher pressure must be exerted on the hand-piece *g* of the suction and pressure piston *e*. By means of the increased pressure thus exerted the lubricant is compressed in the gun cylinder and as soon as the pressure exceeds the tension of the spring *k* the whole gun moves over the working and sliding cylinder *h* of the high pressure pump mechanism somewhat forwardly and the ejection piston *i* thereof enters the cylinder *h*. A portion of the lubricant contents of the cylinder corresponding with the depth of penetration of the piston *i* into the cylinder *h* is thus expelled or ejected under a high pressure. This high pressure corresponds with the differential ratio of the two pistons *e* and *i* and overcomes the resistances which occur at the outlet from the nozzle *l*.

When pressing the nozzle *l* against the point to be lubricated a tight joint must be formed between the two parts which can be obtained in a suitable manner for example by suitable construction of the parts bearing upon one another and the surfaces thereof as also by a suitable application pressure. This tight joint, which when pressing the lubricating gun downwardly prevents the lubricant from escaping laterally, also prevents during the return movement of the lubricating gun of atmospheric air being drawn in as long as the nozzle remains seated on the lubricating hole. Consequently there is formed in the working and sliding cylinder *h* whilst the ejection piston *i* moves out of it under the action of the expanding spring *k*, a vacuum by means of which lubricant is drawn from the supply contained in the gun cylinder *a* at the moment at which the free end of the ejection piston *i* moves out of the working and sliding cylinder *h*. During the return movement of the lubricating gun on the working and sliding cylinder *h* the nozzle *l* is held pressed against the point to be lubricated by the action of the compressed spring *k*. The suction of lubricant into the working and sliding cylinder *h* from the supply contained in the gun cylinder during the relieving from pressure of the device is supported by the pressure of the suction and pressure piston *e* which is under the direct action of the hand and exerted directly on the lubricant before and after the tensioning of the spring *k*.

Each time after the high pressure pump mechanism has come into operation the working and sliding cylinder *h* is immediately again filled with lubricant from the supply contained in the gun cylinder *a*. Both when using the device as an ordinary lubricating gun and as a high pressure lubricating gun the discharge of lubricant is effected through the valveless working and sliding cylinder of the high pressure pump mechanism.

After removing the bottom of the lubricating gun all the parts of the high pressure

pump mechanism can be moved from the front out of the gun cylinder.

I claim as my invention:

1. In a lubricating gun of the class described, a low pressure cylinder forming a container for lubricant, a piston reciprocable in said cylinder and making an air tight and lubricant tight seal therewith when moved in both directions, a high pressure cylinder supplied from said low pressure cylinder, a piston for discharging lubricant from said high pressure cylinder, means for connecting said high pressure cylinder in open communication with a part requiring lubrication, and a handle for moving said low pressure piston in one direction to cause said gun to discharge lubricant and for moving said low pressure piston in a second direction to refill said gun with a new charge of lubricant through the high pressure cylinder.
2. In lubricating apparatus of the class described, a low pressure cylinder forming a lubricant reservoir, a low pressure piston reciprocable in said cylinder, said low pressure piston including reversed cup leathers for effecting an air and lubricant tight seal between said piston and cylinder when said piston is moved in either direction, a high pressure cylinder in communication with said low pressure cylinder, a piston for said high pressure cylinder, a nozzle attached to said high pressure cylinder and providing an open outlet passageway therefor, and a handle for reciprocating the low pressure piston to cause discharge of lubricant under low pressure when moved in one direction and to suck in lubricant through the high pressure cylinder into the low pressure cylinder when moved in the other direction.
3. In a lubricating gun of the class described, a low pressure cylinder forming a container for lubricant, a piston reciprocable in said cylinder and making an air-tight and lubricant-tight seal therewith when moved in either direction, a high pressure cylinder in axial alignment therewith and supplied from said low pressure cylinder, a piston for discharging lubricant from said high pressure cylinder, means for connecting said high pressure cylinder in open communication with a part requiring lubrication, and a handle for moving said low pressure piston in one direction to cause said gun to discharge lubricant and for moving said low pressure piston in an opposite direction to re-fill said gun with a new charge of lubricant through the high pressure cylinder.

In witness whereof I have hereunto set my hand.

HANS KREIDEL.
